UNITED STATES PATENT OFFICE.

SAMUEL L. DENNEY, OF LINCOLN UNIVERSITY, PENNSYLVANIA.

TRAP-NEST.

1,166,191.

Specification of Letters Patent. Patented Dec. 28, 1915.

Application filed May 5, 1915. Serial No. 26,038.

To all whom it may concern:

Be it known that I, SAMUEL L. DENNEY, a citizen of the United States, residing at Lincoln University, in the county of Chester and State of Pennsylvania, have invented certain new and useful Improvements in Trap-Nests, of which the following is a specification, reference being had to the accompanying drawings.

10 This invention relates to certain improvements in trap nests; and it is an object of the invention to provide a device of this general character having novel and improved means whereby a hen is automatically locked within the nest until released through the medium of mechanism controlled by an egg dropping from said nest.

Furthermore, it is an object of my invention to provide a novel and improved device of this general character including a movable floor operatively engaged with the closure member for the entrance opening for the nest whereby said closure member is adjusted into closed position upon movement of the floor together with means whereby said floor is automatically locked against movement in an opposite direction.

20 The invention also has for an object to provide a device of this general character including novel and improved means whereby the floor is released from the influence of the automatic holding means by the hen as she leaves the nest.

25 It is a still further object of my invention to provide a novel and improved device of this general character including a rotatably supported receptacle adapted to receive the eggs as dropped from the nest and adapted to be intermittently rotated by the movable floor.

30 The invention consists in the details of construction and in the combination and arrangement of the several parts of my improved trap nest whereby certain important advantages are attained and the device is rendered simpler, less expensive and otherwise more convenient and advantageous for use, all as will be hereinafter more fully set forth.

35 The novel features of the invention will be carefully defined in the appended claims.

40 In order that my invention may be the better understood, I will now proceed to de-

scribe the same with reference to the accompanying drawings, wherein—

Figure 1 is a view in end elevation of a trap nest constructed in accordance with an embodiment of my invention; Fig. 2 is 60 an end elevation of my present invention opposite to that shown in Fig. 1; Fig. 3 is a sectional view taken substantially on the line 3—3 of Fig. 1, in the direction of the arrow; Fig. 4 is a sectional view taken 65 substantially on the line 4—4 of Fig. 3; Fig. 5 is a fragmentary view, partly in elevation and partly in section, of the exit end of the nest illustrating in detail the means for locking the movable floor in its position assumed under the influence of the weight of the hen; and Fig. 6 is a longitudinal sectional view taken at substantially the transverse center of the movable floor.

As disclosed in the accompanying drawings, 1 denotes a base plate of predetermined configuration but herein disclosed as substantially rectangular in form and having projecting upwardly therefrom adjacent the corners thereof the uprights or 70 posts 2, the uprights at the entrance end of the device being of a greater height than the uprights at the exit end in order to permit the use of the roosting board 3 at the entrance end of the nest so that the hen 75 may enter by a jump.

The longitudinally related posts 2 are connected by the beams 4 arranged in parallelism with the base plate 1 while the posts or uprights at the exit end of the nest are 80 connected by the transverse beam 5 disposed in the same horizontal plane as occupied by the beams 4.

85 Mounted for rocking movement about a horizontal axis and at a point intermediate its length is the movable floor 6 snugly fitting between the roosting board 2 and the longitudinal and transverse beams 4 and 5, with the rotating axis positioned in close proximity to the roosting board 3. The exit 90 end of the floor 6 is normally maintained elevated by the coil spring 7 surrounding the key 8 threaded through one of the posts 2 at the entrance end of the nest and disposed transversely of the device, one extremity of said spring being operatively engaged, as at 9, with the under surface of the floor 6 adjacent its entrance end while the opposite extremity of the spring is secured, as indicated at 10, to the key. It will be readily 95 100 105 110

perceived that upon imparting the requisite axial rotation to the key 8, the tension of the spring 7 may be regulated as desired.

The sides of the device above the beams 4 5 are closed by the imperforate walls 11 and the top of the device is closed by the imperforate member 12. The entrance end of the device above the roosting board 3 is adapted to be closed by the swinging door 14 movable 10 about a horizontal axis 15 adjacent its upper end and the upper portion of said door is provided with the inwardly disposed eye member 16 to afford an operative connection with the rigid link 17 also operatively engaged, as indicated at 18, with the arm 19 carried by the floor 6 and extending exteriorly of the nest whereby it will be perceived that with the exit end of the floor 6 elevated, the door 14 is also elevated or in 20 open adjustment and vice versa. It will be perceived that when the hen jumps from the roosting member 3 upon the floor 6, the exit end of the floor will be depressed and the door 14 moved into closed adjustment 25 and said floor is automatically locked in its depressed adjustment by the cam member 20 rotatably supported by the beam 5 and adapted to bear against the adjacent end of the floor 6, as is particularly shown in detail Fig. 5. It is also to be observed in this 30 figure that the wear plate 21 is preferably employed with its outer surface serrated, as is the periphery of the cam 20.

The cam 20 is provided with the tail 22 35 extending exteriorly of the nest and with which is pivotally engaged an extremity of the rod 23, the opposite extremity of which being provided with the elongated loop 24 through which is extended a projection 25 40 extending laterally from the swinging door 26 for the exit end of the nest, said door being movable about the horizontal axis 27 adjacent its upper extremity. It will be readily perceived that the loop 25 permits a 45 limited independent movement of the door 26, but upon its elevation during the exit of the hen the cam 20 through the medium of the rod 23 will be disengaged from the floor 6 whereby the same may return to its 50 normal position under the tension of the spring 7.

Depending from the beam 5 is a vertical member 28 with which is slidably engaged for vertical movement, the arm 29, the upper extremity of which being provided with the gravity pawl 30 adapted to overlie the lower marginal portion of the door 26 and maintain the same in closed adjustment. Depending from the floor 6 adjacent its rotative axis and in alinement with the vertical member 28 is a plate 31 and rotatably supported by said plate 31 and vertical member 28 is a rock shaft 32, the outer extremity of which being provided with a crank 33 55 extending within the open end recess 34 dis-

posed transversely of the arm 29 whereby it will be readily perceived that upon requisite rocking movement being imparted to the shaft 32, the arm 29 will be raised or lowered.

As herein embodied, the shaft 32 is received within an open slot 35 produced in the member 28 and with which coacts the swinging plate 36 of a length to overlie the slot 35 and thus retain the shaft 32 against displacement. Surrounding the shaft 32 is the coil spring 37, one extremity of which being operatively engaged with the member 28 with the opposite end thereof secured to the head 38 fixed to the shaft 32, the tension of said spring 37 being such as to normally maintain the arm 29 at the limit of its upward movement so that the gravity pawl 30 may operatively engage the lower marginal portion of the door 26 upon its return after the hen has left the nest. The upper surface of the floor 6 is suitably recessed as indicated at 39 in Fig. 6, for a purpose which is believed to be clearly apparent to those skilled in the art to which my invention appertains, and at substantially its axial center the floor 6 is provided with the opening 40 through which the egg is adapted to drop, said opening being defined by the depending flange 41 to which is suitably secured the chute 42, said chute having one side portion of its lower or free extremity cut-away, as at 43, to permit said chute to be intersected by the rock arm 44 carried by the shaft 32 whereby it will be perceived that as the egg falls through the chute 42, the shaft 32 will be so rocked as to move the arm 29 downwardly and thus permit the hen to escape as the door 26 may be readily raised or swung upwardly by the hen. In order, however, that the door 26 may be initially elevated a predetermined distance when the pawl 30 is disengaged therefrom, I provide the upper marginal portion of the door 26 with the inwardly disposed eye member 45 to afford an operative connection with the rod 46 extending downwardly and through the slot 47 in the exit end of the floor 6, said slot being indicated by dotted lines in Fig. 6. The lower extremity of said rod 46 is provided with the head 48 with which contacts the lower extremity of the coil spring 49 embracing the rod 46 below the floor 6 and adapted to be compressed or placed under tension upon the depression of the exit end of the floor but the spring 49 does not possess sufficient tension when compressed to raise the door 26 a distance sufficient to release the cam 20 from the floor 6.

Positioned within the depressed portion 39 of the floor 6 is the nest egg 50 maintained against displacement through the medium of the flexible member 51 anchored to the floor 6 adjacent the entrance end thereof and

as is particularly shown at 52 in Fig. 6, and it is to be observed that the flexible connection 51 is of such a length as to permit the nest egg 50 to partially overlie the opening 40 so that said opening may not serve to deter the hen from entering the nest. Rotatably supported by the base plate or member 1 is the receptacle 53 of predetermined configuration and provided with the yieldable lining 54 to prevent injury of the egg dropped within the container through the opening 40 and operatively engaged as at 55, with the vertically disposed supporting shaft 56 of the container 53 is the shaft 57 disposed in parallelism with the base plate or member 1 and having operatively engaged with its outer extremity the ratchet crank 58 with which is pivotally engaged the rod 59 also pivotally engaged, as at 60, with the entrance end of the floor 6 whereby it will be readily perceived that the container 53 will be intermittently rotated under the influence of the oscillations of the floor 6.

25 In view of the foregoing, it will be readily seen that as the hen jumps upon the floor 6, the said floor will be depressed resulting in the closing of the door 14, and the hen will be confined therein until the 30 door 26 is released by the dropping of an egg through the opening 40. As the hen escapes, the door 26 is elevated whereupon the cam 20 is disengaged from the floor 6 whereby the same will return to its normal 35 or elevated position under the tension of the spring 7 and return the door 14 to an open position. After the hen has left the nest, the door 26 will return by gravity to its closed position and being maintained 40 in such closed position by the pawl 30. The manner whereby the egg is caused to disengage the pawl 30 from the door 26 when in closed position and whereby said door 26 is caused to assume a partially open position, has been hereinbefore set forth in detail.

From the foregoing description, it is thought to be obvious that a trap nest constructed in accordance with my invention is of an extremely simple and comparatively inexpensive nature and is particularly well adapted for use by reason of the convenience and facility with which it may be assembled, and it will also be obvious that my invention is susceptible of some change and modification without material departure from the principles and spirit thereof and for this reason I do not wish to be understood as limiting myself to the precise arrangement and formation of the several parts herein shown in carrying out my invention in practice.

I claim:

1. A nest of the character described comprising a housing provided with an entrance

opening and an exit opening, a depressible floor positioned within the housing, a closure for the entrance opening, an operative connection between the floor and said closure whereby the closure is adjusted into closed 70 position upon depression of the floor, automatic means for maintaining the floor in its depressed adjustment, a closure member for the exit opening of the housing, and means controlled by the last named closure member for releasing the automatic means.

2. A nest of the character described comprising a housing provided with an entrance opening and an exit opening, a depressible floor positioned within the housing, a closure 80 for the entrance opening, an operative connection between the floor and said closure whereby the closure is adjusted into closed position upon depression of the floor, automatic means for maintaining the floor in its 85 depressed adjustment, a closure member for the exit opening of the housing, and means controlled by the last named closure member for releasing the automatic means, said last named closure being capable of movement independently of the means coacting therewith for releasing the automatic means.

3. A nest of the character described comprising a housing provided with an exit 90 opening, a closure for said exit opening, a depressible floor within the housing and provided with a discharge opening, means carried by the housing engageable with the floor for automatically maintaining the 100 same in its depressed adjustment, a latch for maintaining the closure member in closed position, means controlled by an egg dropped through the discharge opening of the floor for releasing the latch, and means 105 coacting with the movable floor and the closure member for imparting initial movement thereto into an open position.

4. A nest of the character described comprising a housing provided with an exit 110 opening, a closure for said exit opening, a depressible floor within the housing and provided with a discharge opening, means carried by the housing engageable with the floor for automatically maintaining the 115 same in its depressed adjustment, a latch for maintaining the closure member in closed position, means controlled by an egg dropped through the discharge opening of the floor for releasing the latch, means coacting with the movable floor and the closure member for imparting initial movement thereto into an open position, and means operable upon further movement of the closure member in opening adjustment to release the automatic means for maintaining the floor in depressed adjustment.

5. A nest of the character described comprising a housing provided with an exit 120 opening, a depressible floor positioned with- 130

in the housing, a closure member for said exit opening mounted for swinging movement in the same general direction as the direction of movement of the floor, a latch 5 for maintaining the closure member in closed adjustment, means for releasing the latch, a rod operatively engaged with the closure member and terminating below the 30 depressible floor, and an expansible member carried by the rod engageable with the under surface of the depressible floor, said

expansible member being placed under tension upon depression of the floor and serving to impart initial movement to the closure member upon release.

In testimony whereof I hereunto affix my signature in the presence of two witnesses.

SAMUEL L. DENNEY.
